LIQUID DISPENSING APPARATUS

Filed Dec. 29, 1927

Benjamin Konipol
INVENTOR

ROBERT W. LYNN
ATTORNEY

UNITED STATES PATENT OFFICE

BENJAMIN KONIPOL, OF NEW YORK, N. Y.

LIQUID DISPENSING APPARATUS

Application filed December 29, 1927. Serial No. 243,314.

My invention relates particularly to means for measuring milk or other liquids where sanitary protection is important.

The main object is to provide simple, reliable and sanitary apparatus for accurately measuring milk. Modern sanitary and economic requirements with respect to the sale of milk are very exacting. Local ordinances generally require accurate measuring and a complete enclosure of milk held in bulk. In many places the requirements are so exacting that the dealer is not allowed to fill milk bottles from the usual bulk containers or cans. Various forms of enclosed measuring devices have been heretofore proposed, but so far as I am aware they are all either complicated and expensive or likely to be inaccurate and unreliable in their operation.

Another object is to ensure a complete and repeated stirring of the liquid.

According to my invention, I provide a ladle or measuring device consisting of a dipper having an upright handle, the lower end of which is hinged to the dipper. The side of the dipper is detachably secured to the handle for the purpose of measuring the milk. The handle passes through the cover and is provided with means for automatically tilting the dipper and discharging the contents from a spout at one side.

Fig. 1 is a vertical section of apparatus embodying my invention showing in dotted lines the relative position of the dipper in the filling and discharging positions, and showing the dipper in cross section in an intermediate position after discharge of the contents.

Fig. 2 is a detail sectional view showing the dipper about to be tilted for discharging.

Fig. 3 is a plan view of the dipper showing the handle in section.

The can 5 is intended to illustrate any form of can which is usually kept in some form of a refrigerator or container 6.

The invention contemplates the use of a special hood 7 having a neck 8 which will fit into the mouth of the can, a stop flange 9 which will overlap the neck of the can and a suitable cover 10 which is preferably removable and which may be held in place by any suitable means, such as clips 11 hinged to the

upper part of the hood. The cover may be provided with a handle 12. The hood is provided with a discharge spout 14 which may be provided with a hinged or removable cap 15 normally closing it. This nozzle should be long enough to extend beyond the edge of the usual refrigerating container. The dipper 16 may be of any suitable construction and of any desired capacity. The handle or rod 17 has a foot 18 bent at an angle and hinged to the bottom of the dipper at a point between the center of the dipper and the handle 17, so that the weight of the dipper and contents tends to tip or tilt the dipper away from the handle. The dipper is provided with a pair of spring clips 19 near its upper edge adapted to frictionally engage the edges of the handle and hold the dipper upright with its upper edge horizontal.

The spring 20 is secured to the lower end of the handle beneath the dipper and serves two purposes. It serves as a yielding check for the downward movement of the dipper and handle into the can and it also serves as a stop for limiting the tilting movement of the dipper, as shown at the top of Fig. 1.

The cover is provided with a slot 21 through which the handle passes. A guide 22 may be provided to facilitate the insertion of the handle through the cover. The handle itself may be provided with a cap 23 adapted to cover the opening when the handle is down.

The wedge 24 secured to the cover alongside of the slot 21 serves as a disengaging member and is adapted to fit between the upper edge of the dipper 16 and the handle 17 when the dipper is raised to the position shown in Fig. 2. The cam-like member 25 may be secured to the edge of the dipper to co-act with the wedge 24. This wedge 24 as the dipper is raised forces the edge of the dipper away from the handle, and thus disengages the spring clips 19 and allows the eccentrically loaded dipper to discharge its contents into the spout 14.

I also prefer to provide a receiving pocket 26 at the entrance to the spout 14 so that all of the milk will be certain to be collected and discharged.

As the handle is released the dipper will

be tilted back toward the handle by its engagement with the partition 27 and the inside of the neck 8, as shown in Fig. 1. As the dipper is moved below the center, as viewed in Fig. 1, it will again tilt or swing about its hinge connection with the handle so as to bring the open end downward into the milk, and thus stir up the milk as the handle and dipper are moved to the bottom of the can. 10 This latter is a very important feature since with many dispensing devices and measuring devices it is possible to dip into the can and take up only the thinner milk at the bottom. 15 With my improved device, however, every time that the dipper is used the entire contents of the can is thoroughly stirred. As the dipper strikes the bottom of the can the clips 19 are again brought into play to connect or secure the side of the dipper to the handle, and thus hold the dipper in its proper position for further use.

The cover may be provided with a window 28 if desired.

It should be understood that spring means 25 might be provided either for lifting the dipper and handle or depressing them. It should also be understood that any number of dippers of various sizes might be employed with the same receptacle each operating in 30 the manner herein set forth.

The same construction can, of course, be used for measuring out liquids, such as, orangeade and lemonade, or other liquids when accuracy and cleanliness are particularly desired.

The liquid is kept entirely enclosed at all times just as it would be in a bottle or sealed container.

It will be seen that the discharge funnel 40 consisting of the pocket 26 and spout 14 is kept closed at the top at all times and the contents of the dipper are discharged into the upper part of this funnel from which there is an opening leading to the outside. Not only 45 is the can kept closed at all times, but the dipper and discharge funnel are never exposed to outside dust or other contaminating influences.

I claim:

50 1. A liquid measurer, comprising a dipper, a handle having an angular foot hinged beneath the dipper and spring means cooperating with said dipper and handle for detachably securing the side of the dipper to the handle.

55 2. A liquid measurer, comprising a dipper, a handle having an angular foot hinged beneath the dipper and means for detachably securing the side of the dipper to the handle, means for limiting downward movement of said dipper and handle and a kick-off spring secured to the foot beneath the dipper for cooperation with said limiting means.

60 3. A liquid measurer, comprising a dipper, a handle having a foot hinged beneath the

dipper, spring means cooperating with said dipper and handle for detachably securing the side of the dipper to the handle, and a spring for cooperation with said handle and dipper to limit tilting of said dipper beneath 70 the dipper.

4. A liquid measurer, comprising a container having a side trough and a cover, a tilting dipper having a handle movable through the cover, spring means for interlocking the dipper and handle, and a wedge carried by the cover for releasing said spring means and tilting the dipper.

5. Liquid dispensing apparatus comprising a can having a mouth, a detachable hood having a neck fitted to said mouth, said hood having a laterally projecting spout with a receiving pocket in the upper part of said hood, a detachable cover for said hood and pocket, a dipper having a substantially rigid 80 handle one end of which is hinged to one side of the dipper and the other end of which extends through said cover, and means for tilting the dipper when the handle is raised so as to discharge the contents of the dipper into 85 said pocket, said dipper being tilted by gravity when the handle is lowered into the can.

6. A liquid measurer, adapted to fit on a container and comprising a cover for the container, a dipper, a rod projecting through the cover for raising and lowering the dipper and having the dipper hinged thereto adjacent one side of the dipper bottom, yieldable means engaging said rod for holding the dipper when filled, means for releasing said dipper holding means to permit tilting of the dipper, and a passage arranged to receive the dipper contents as the dipper is tilted by said releasing means.
